(57) **CLAIM**

The ornamental design for a nail clipper, as shown and described.

DESCRIPTION

FIG. 1 is a perspective of the nail clipper incorporating my new design with the lever arm in the upward position;
FIG. 2 is a side view with the opposite side view being a mirror image thereof;
FIG. 3 is a right end view;
FIG. 4 is a left end view;
FIG. 5 is a bottom view;
FIG. 6 is a top view;
FIG. 7 is a side view with the lever arm in the downward position;
FIG. 8 is a right end view of FIG. 7;
FIG. 9 is a left end view of FIG. 7;
FIG. 10 is a bottom view of FIG. 7;
FIG. 11 is a top view of FIG. 7;
FIG. 12 is a side view with the lever arm and file arm in the extended position with the opposite side view being a mirror image thereof;
FIG. 13 is a right end view of FIG. 12;
FIG. 14 is a left end view of FIG. 12;
FIG. 15 is a bottom view of FIG. 12; and,
FIG. 16 is a top view of FIG. 12.
